UNITED STATES PATENT OFFICE.

ALBERT F. PRESTON, OF BOSTON, MASSACHUSETTS.

CUTTER-HEAD AND CUTTER.

1,208,371.

Specification of Letters Patent. Patented Dec. 12, 1916.

Original application filed October 10, 1912, Serial No. 725,075. Patent No. 1,105,534, dated July 28, 1914.
Divided and this application filed March 4, 1914. Serial No. 822,823.

To all whom it may concern:

Be it known that I, ALBERT F. PRESTON, a citizen of the United States, and resident of Boston, in the county of Suffolk and State 5 of Massachusetts, have invented certain new and useful Improvements in Cutter-Heads and Cutters, of which the following is a specification.

The present invention relates to an improved cutter head and detachable cutter therefor.

The specific embodiment of the invention here illustrated has been designed as part of the cutting mechanism of a machine for 15 grading and cutting out patterns, illustrated in my application for patent for power cutting, grading machine, filed October 10, 1912, Serial Number 725,075, patented July 28, 1914, Number 1,105,534, and was originally 20 claimed in said application. The present application is a division of that above identified.

The principles of the invention involved in the herein described cutter head and cutter are applicable to many varied uses and machines, in addition to the use and machine in connection with which the invention is here illustrated.

The object of the invention is to provide a 30 simple and inexpensive means by which a cutter may be firmly secured in a cutter head so that there is no danger of its becoming accidentally displaced, while at the same time it can be readily removed when occasion requires.

In the accompanying drawings forming a part of this application, wherein I have illustrated an embodiment of my invention adapted for use in a pattern cutting machine, Figure 1 is a sectional view of the 40 part of such machine in which my improved cutter is embodied. Fig. 2 is an elevation as seen from the left of Fig. 1 of the cutter and the part of the machine in which the same is mounted. Fig. 3 is a section on line 45 3-3 of Fig. 1. Fig. 4 is an elevation in detail of a part of the operating means for the cutter. Figs. 5, 6, and 7 are perspective views showing forms which may be given 50 to the cutter within the scope of my invention for carrying out the particular object of the invention.

The same reference characters indicate the same parts in all the figures.

55 Referring to the drawings the character

11 represents a block or cutter head or holder and 12 represents a cutter mounted in such block.

13 represents a complementary cutter with which the cutter 12 co-operates in severing material. In the machine in which I have shown my improved cutter as being applied, there is a frame consisting in part of jaws 14 and 15 upon which the complementary cutters 12 and 13 are respectively mounted. The block or head 11 is arranged to slide in a guideway 16 at one end of the jaw 14, and is retained in such guideway by a cover plate 17. It is reciprocated by a shaft 18 turning in bearings in the jaw 14 and carrying an eccentric crank pin 19 on which there is mounted an antifriction roll 20. Such roll enters a notch or recess 21 in the back of the cutter block 11, in which it is free to travel laterally while moving the block back and forth. In the embodiment of the invention here shown the block 11 is narrower than the outer circumference of the path in which the roll 20 travels, wherefore the sides of the guideway are enlarged 60 at 22 and 23 to permit complete rotation of the roll. These enlargements, however, are details which concern only the particular machine wherein the invention is here shown as being used, and are not limiting 65 features of the invention. The knife 12, being operated reciprocatively as above described, travels so that the cutting edge 24 at the projecting end moves toward and from the complementary edge of the stationary cutter 13, and may cross such complementary edge. The stationary cutter is preferably a disk having its cutting edge formed between its periphery and its rear face, and it is secured to the jaw 15 by a screw 25 in 70 the center of the disk, which screw may be loosened to permit turning of the disk when a used portion of its edge becomes dull, so as to present a sharp unused portion of the edge adjacent to the path of the knife 12.

75 The feature in which my present invention particularly resides relates to the co-operative construction of the cutter block 11 and knife 12. The knife here shown is made of a section cut from a prismatic bar of steel or other material, one end of which is formed with a cutting edge 24 and the other end of which is inserted in a socket in the block 11. Preferably the block is reversible and contains two sockets 26, one at 80 85 90 95 100 105 110

each end and each adapted to contain the knife 12 or a duplicate of such knife. The shape of the socket corresponds to the shape of the butt end of the knife and is so nearly 5 of the same size that the knife has a close fit therein. The knife is retained in the socket by being distorted from its true prismatic shape, either by being bent or sprung between its ends, as shown in Fig. 5, or by 10 being twisted as shown in Fig. 6, or by being both bent and twisted as shown in Fig. 7. This distortion is given to the knife before the latter is hardened and tempered, whereby the knife receives a permanent set 15 which is resilient and permits of elastic distortion back to a form approximating that of the socket. Thus when the knife is forced into the socket it is caused to bind against the walls of the socket with a resili- 20 ent pressure sufficiently powerful to prevent the knife from falling or jarring out of the socket. The knife may, however, be readily enough removed when necessary by the application of positive force sufficient to over- 25 come the resilient binding of the knife in the socket. For this purpose the knife block has a passage 27 leading from the bottom of the socket into the notch 21 occupied by the driving roll. A similar passage leads from 30 the socket at the other end of the block and both passages are in alinement. Thus when the block 11 is removed from its guide a pin may be passed through the open socket and the alined passages 27 and may be used 35 to drive out the knife.

I do not intend to limit my invention to a cutter or knife which is prismatic in form, since the principles of the invention may be applied as well to knives of other forms in 40 cross section. The quality of binding which is given to the knife by having a permanent bend formed in it, may be given to a knife of any form, even when such form is the extreme one of a cylindrical punch. The capability of binding which is given by twisting the knife may be applied to almost any form of knife or punch except that which is circular in cross section. The important 45 feature of the invention is that that portion, or shank of the knife which enters the socket in the holder is of elastic material and is of such shape that in being inserted into the socket, it is elastically distorted. Obviously many other forms of knife than 50 those illustrated may be made in accordance with this distinction of my invention.

The invention is not limited to a knife having a single straight cutting edge, or to 55 a knife carrying block of the form shown in the drawings, or to a block of any form having neither more nor less than two knife receiving sockets. A knife or cutter of any form, whatever may be its cross sectional outline or the outline of its cutting edge, 60 may be made in accordance with my inven- 65

tion, provided the essentials above indicated are followed, and a knife holder of any shape and character, whether movable or stationary, and adapted to be moved by any means whatever, is also within the scope of 70 my invention when complying with such essentials.

What I claim and desire to secure by Letters Patent is:

1. The combination of a knife and its 75 holder, said holder having a socket of approximately the same shape and size as a portion of the knife, and the knife being permanently set out of exact accordance with the form of the socket, and being of elastic 80 material, whereby said knife upon being inserted in the socket is distorted elastically and caused to bind resiliently against the walls of the socket.

2. The combination of a knife block or 85 holder and a knife, said block having a socket adapted to receive one end of the knife, and the knife being of such form approximately the same as that of the socket but slightly out of true therewith, that 90 when inserted into the socket the knife is sprung from its normal shape and caused to bind resiliently against the walls of the socket.

3. The combination of a cutter having a 95 shank in the form of a bar, non-circular in cross section and a cutter carrier having a socket shaped similar to and of a size to fit closely about the bar, the bar being both twisted and bent so as to bind resiliently in 100 the socket.

4. The combination of a cutter having a shank in the form of a bar, non-circular in cross section and a cutter carrier having a 105 socket shaped similar to and of a size to fit closely about the bar, the bar being bent out of true with the socket sufficiently to bind resiliently against the walls of the socket.

5. The combination of a cutter having a shank in the form of a bar, non-circular in 110 cross section and a cutter carrier having a socket shaped similar to and of a size to fit closely to the bar, the bar being twisted sufficiently to bind resiliently against the walls of the socket when forced thereinto.

6. The combination of a cutter holder having a straight socket, and a cutter in the form of a bar shaped so as to fit said socket and being of elastic material and having a permanent bend, whereby the cutter is elastically distorted when inserted into said socket and caused to bind against the sides thereof.

7. The combination of a cutter block or holder having a socket and a cutter or knife having a shank adapted to enter said socket, the said socket and cutter shank being of similar form and size in cross section, and the shank having a permanent set out of the exact form of the socket, whereby said shank 115

upon being inserted in the socket is elastically distorted and caused to bear against the walls of the socket.

8. The combination of a cutter block or holder having a socket and a cutter or knife having a shank adapted to enter said socket, the said socket and cutter shank being of similar form and size in cross section, and the shank having a permanent set out of the exact form of the socket, whereby said shank upon being inserted in the socket is elastically distorted and caused to bear against the walls of the socket, and the holder having a passage running from the socket adapted to receive an instrument for expelling the knife therefrom.

9. A cutter instrument comprising in combination, a block having a socket which is non-circular in cross section and having a passage running from the bottom of the socket and open at the end opposite to the socket for insertion of a driving pin, and a cutter or knife having a shank of the same

shape and area in cross section as the socket and having a permanent twist, whereby it is distorted, forced into the socket and caused to bind therein.

10. A cutter instrument comprising a block having sockets in its opposite ends and passages extending from the bottoms of the respective sockets, said sockets and passages being in alinement, whereby the instrument may be passed from one socket to the other, and a knife having a shank of the same form and area in cross section as either socket adapted to be inserted therein, and also having a permanent set out of true with the socket, whereby it is elastically distorted when so inserted and is caused to bind against the walls of the socket.

In testimony whereof I have affixed my signature, in presence of two witnesses.

ALBERT F. PRESTON.
